ILLUMINATED SIGNAL

Henry Dreyfuss, South Pasadena, Calif., assignor to Bell Telephone Laboratories, Incorporated, Murray Hill, N.J., a corporation of New York

Filed Dec. 29, 1967, Ser. No. 9,997

Term of patent 14 years

Int. Cl. D29—99; D26—99

U.S. Cl. D72—1

FIG. 1

FIG. 4

FIG. 2

FIG. 5

FIG. 3

FIG. 6

FIG. 7

FIG. 8

FIG. 9

FIG. 1 is a perspective view of the single form of my new design for an illuminated signal;

FIG. 2 is a side view of the illuminated signal shown in FIG. 1, the opposite side having substantially the same appearance;

FIG. 3 is a front view of the illuminated signal shown in FIG. 1, the rear view having substantially the same appearance;

FIG. 4 is a perspective view of the double form of my new design for an illuminated signal;

FIG. 5 is a side view of the illuminated signal shown in FIG. 4, the opposite side having substantially the same appearance;

FIG. 6 is a front view of the illuminated signal shown in FIG. 4, the rear view having substantially the same appearance;

FIG. 7 is a perspective view of the triple form of my new design for an illuminated signal;

FIG. 8 is a side view of the illuminated signal shown in FIG. 7, the opposite side having substantially the same appearance; and

FIG. 9 is a front view of the illuminated signal shown in FIG. 7, the rear view having substantially the same appearance.

I claim:

The ornamental design for an illuminated signal, substantially as shown and described.
